[57] CLAIM

The ornamental design for a bottle, as shown and described.

DESCRIPTION

FIG. 1 is a top plan view of a bottle showing my new design; FIG. 2 is a front elevation view thereof, the opposite side being identical;

FIG. 3 is a bottom plan view thereof;

FIG. 4 is a left side elevation view thereof, the right side being identical;

FIG. 5 is a perspective view thereof, with only a portion of the repeat floral pattern shown for ease of illustration; and, FIG. 6 is a front elevation view of a second alternate embodiment, the top, bottom, left and right side views are the same as the corresponding views of the first embodiment.
